UNITED STATES PATENT OFFICE.

WILLIAM E. ROSS, OF CLEVELAND, OHIO, ASSIGNOR TO THE ROSS MANUFACTURING COMPANY, OF CLEVELAND, OHIO, A CORPORATION OF OHIO.

DRESSING-TOOL.

1,348,323.

Specification of Letters Patent.

Patented Aug. 3, 1920.

Application filed May 13, 1919. Serial No. 296,899.

To all whom it may concern:

Be it known that I, WILLIAM E. Ross, a citizen of the United States, and resident of Cleveland, county of Cuyahoga, and State of Ohio, have invented new and useful Improvements in Dressing-Tools, of which the following is a specification, the principle of the invention being herein explained and the best mode in which I have contemplated applying that principle, so as to distinguish it from other inventions.

My invention relates to dressing tools and particularly to tools of this nature utilized for dressing worn surfaces of grinding wheels. More particularly, my invention relates to improvements in means for rotatably mounting the dressing element in a supporting member, and improvements in various detailed features of the mounting itself.

The annexed drawing and the following description set forth in detail certain means embodying my invention, the disclosed means, however, constituting but one of the various mechanical forms in which the principle of the invention may be employed.

In said annexed drawing:

Figure 1 represents a side elevation of my improved tool;

Fig. 2 represents a plan view, a protecting hood of the supporting member being broken away;

Fig. 3 represents a vertical longitudinal section, taken in the plane indicated by the lines III—III, Fig. 2;

Fig. 4 represents a vertical transverse section, taken in the plane indicated by the line IV—IV, Fig. 2;

Figs. 5 and 6 represent, respectively, face and side views of a dressing element;

Fig. 7 represents a perspective view of a rotatable spindle;

Fig. 8 represents a perspective view of a lock nut disposed internally of the supporting member in a manner and for a purpose hereinafter fully explained;

Fig. 9 represents a perspective view of a cylindrical core or spool to which the dressing element is secured;

Fig. 10 represents a perspective view of an internal bushing; and

Fig. 11 represents a perspective view of one of a pair of washers between which the assembly of dressing elements are secured.

Referring to the annexed drawing, the

dressing member proper entering into my improved tool consists of a plurality of thin flat disks 1 provided with spaced teeth 2, of substantially the design and construction plainly shown in Figs. 5 and 6. The dressing member comprised of this plurality of elements 1 is directly supported upon a cylindrical core or spool 3 of soft steel, the ends of said spool 3 being upset to form binding flanges 3' between which the plurality of elements 1 is rigidly confined, suitable washers 4 being disposed at the ends between the outermost elements 1, respectively, and the adjacent flanges 3'. The several disks 1 are so positioned upon the spool 3 that the edges 70 of the teeth 2 are disposed spirally across the face of the dressing member, the exact and proper position of each of the disks 1 being secured by tapping the teeth 2 thereof, with a suitable hammer or other tool, after 75 the element has been placed over the spool 3 and before finally and completely upsetting the ends of said spool into the flanges 3'. The spool 3 is further directly connected to an internally disposed cylindrical shell or 80 bushing 5 of comparatively hard steel, said bushing being formed with a series of longitudinally disposed splines 6, as plainly shown in Fig. 10. The external diameter of the bushing 5 is slightly greater than the 85 internal diameter of the spool 3 and said bushing is fitted within said spool by driving the same therein, the bushing 5 slightly expanding the soft shell 3 and the splined edges of the comparatively hard bushing 90 cutting their way through the inner surfaces of the comparatively soft metal of which the spool 3 is comprised. The result is plainly shown in Figs. 3 and 4. Two shoulders 7 are formed upon one end of the bushing 5 95 for a purpose hereinafter fully explained. The construction so far explained results in a complete and unitary assembly of the dressing element. It is now necessary to secure this element to a suitable rotatable 100 spindle, and provide suitable bearings in a suitable supporting member for said rotatable spindle. This construction will now be explained in detail.

The spindle is designated by the ordinal 105 8 provided with threaded end portions 9 and 10. Said spindle is also provided intermediately of its ends and to one side of the center thereof with a shoulder 11 formed with depressions 12 adapted to interlock 110

with the shoulders 7 of the bushing 5, whereby relative movement of said bushing along the spindle 8 in one direction is prevented and the said bushing 5 is secured to said 5 rotatable spindle 8. The spindle 8 is also provided with a threaded portion 13 intermediately of its ends and disposed upon that side of the center thereof opposite to the side upon which the shoulder 11 is formed. 10 By means of an internally disposed nut 18 adapted to coöperate with the threaded portion 13, and of the design plainly shown in Fig. 8, the relative longitudinal movement of the bushing 5 and the spindle 8 in the other direction, is prevented. This 15 assembly is plainly shown in Fig. 4 and the manner in which such assembly is secured will now be explained in detail.

Assuming that the unitary dressing member 20 has been assembled in the manner hereinbefore explained, the same is inserted between the arms 16 of a yoke-shaped member forming the main support, adapted to be secured to a suitable handle 15, and 25 formed with a protecting hood 17. When said dressing element is inserted between the arms 16, the nut 18 is lying loosely in a shallow cavity 18' formed intermediately of one end of the bushing 5 and the adjacent 30 flange 3' of the spool 3. The end 9 of the spindle 8 is inserted through the enlarged hole 17' of one arm 16 and the spindle passed through the central aperture of the bushing 5 until the shoulders 7 35 and slots 12 are interlocked, the end 9 having meanwhile passed through the nut 18 and into the comparatively small hole 17² of the other yoke arm 16. A suitable wrench is then inserted down between the 40 dressing member and the last-mentioned yoke arm 16 and the nut 18 tightened upon the thread 13 until the dressing member is drawn over toward said yoke arm 16 and suitably centralized between the two arms 45 16. The spindle portion 13 is formed with a suitable cotter pin hole 14 and the nut 18 with corresponding hole 14' so that the nut 18 can be secured in position by a suitable cotter pin, as plainly shown in Figs. 2 and 4. 50 The bearings for the rotatable spindle 8, the means of adjusting, and the means for securing, the spindle in the supporting member, will now be described in detail. Suitable felt washers 20 are positioned in the 55 holes 17' and 17² adjacent the shoulder 11 and the contiguous portion of one of the yoke arms 16, respectively, as plainly shown in Fig. 4. The yoke arms 16 are respectively provided with bearing members 17³ 60 and journaled therein are suitable ball bearing elements 21 formed with bearing surfaces for the respective ends of the spindle 8. Said bearings 21 are held to position by plate washers 23 rigidly secured by means 65 of nuts 22 internally threaded to coöperate

with the threaded end portions 9 and 10 of the spindle 8. In addition to securely positioning the spindle 8 within the supporting member, said nuts 22 provide means for effecting adjustment of the rotating element 70 in the supporting member, as desired.

What I claim is:

1. A dressing tool comprising, a dressing element; a rotatable spindle; a supporting member provided with spindle bearings; means for securing said spindle in said supporting member; and means for securing said dressing element to said spindle so that the same may rotate together, said means comprising outer and inner cylinders respectively secured to said element and said spindle, the exterior diameter of said inner shell being somewhat greater than the interior diameter of said outer shell, said shells being driven one within the other. 85

2. A dressing tool comprising, a dressing element; a rotatable spindle; a supporting member provided with spindle bearings; means for securing said spindle in said supporting member; and means for securing said dressing element to said spindle so that the same may rotate together, said means comprising soft metal and comparatively hard metal cylinders secured one to said element and one to said spindle, the inner 95 diameter of one shell being somewhat smaller than the exterior diameter of the other shell, said shells being driven one within the other.

3. A dressing tool comprising, a dressing element; a rotatable spindle; a supporting member provided with spindle bearings; means for securing said spindle in said supporting member; and means for securing said dressing element to said spindle so that the same may rotate together, said means comprising soft metal and comparatively hard metal cylinders secured one to said element and one to said spindle, the inner 100 diameter of one shell being somewhat smaller than the exterior diameter of the other shell, said shells being driven one within the other, the contacting surface of the hard metal shell being formed with cutting splines. 110

4. A dressing tool comprising, a dressing element; a rotatable spindle; a supporting member provided with spindle bearings; means for securing said spindle in said supporting member; and means for securing said dressing element to said spindle so that the same may rotate together, said means comprising a soft metal spool to the exterior of which said element is secured and a comparatively hard metal bushing secured to 120 said spindle and formed with exterior splines adapted to be driven into the inner surface of said spool.

5. A dressing tool comprising, a dressing element; a rotatable spindle; a supporting 130

member provided with spindle bearings; means for securing said spindle in said supporting member; and means for securing said dressing element to said spindle so that 5 the same may rotate together, said means including a spindle bushing secured to said element and formed with a shouldered end portion, a shouldered portion formed upon said spindle and adapted to engage with the 10 shouldered portion of said bushing, a threaded portion upon said spindle, disposed adjacently the other end of said bushing, and a coöperating internally threaded member adapted to bear against said last 15 named bushing end.

6. A dressing tool comprising, a dressing element; a rotatable spindle; a supporting member provided with spindle bearings; means for adjustably securing said spindle 20 in said supporting member; and means for securing said dressing element to said spindle so that the same may rotate together, said means including a spindle bushing secured to and interiorly of said element and formed 25 with a plurality of shoulders; shoulders formed upon said spindle and adapted to engage with the shoulders of said bushing; and means for securing said bushing longitudinally relatively to said bushing.

7. A dressing tool comprising, a dressing element; a rotatable spindle; a supporting member provided with spindle bearings; means for securing said spindle in said sup-

porting member; and means for securing said dressing element to said spindle so that 35 the same may rotate together, said means comprising outer and inner cylinders respectively secured to said element and said spindle, the exterior diameter of said inner cylinder being somewhat greater than the 40 interior diameter of said outer cylinder, and means for expanding said outer cylinder to receive and be securely fastened to said inner cylinder.

8. A dressing tool comprising, a dressing 45 element; a rotatable spindle; a supporting member provided with spindle bearings; means for adjustably securing said spindle in said supporting member; means for securing said dressing element to said spindle 50 so that the same may rotate together, said means comprising outer and inner cylinders respectively secured to said element and said spindle, the means securing together said spindle and inner cylinder comprising 55 coöperating shoulders formed upon said cylinder and spindle, and means fixing said cylinder against longitudinal movement relatively to said spindle; the exterior diameter of said inner cylinder being somewhat 60 greater than the interior diameter of said outer cylinder; and means for expanding said outer cylinder to receive and be securely fastened to said inner cylinder.

Signed by me this 3rd day of May, 1919. 65
WILLIAM E. ROSS.
